UNITED STATES PATENT OFFICE

2,565,788

GUN PERFORATOR FOR WELL CASINGS

James O. Tow, Huntington Park, Calif., assignor
to McCullough Tool Company, Los Angeles,
Calif., a corporation of Nevada

Application August 23, 1947, Serial No. 770,231

8 Claims. (Cl. 164—0.5)

1
My invention relates to guns employing an explosive for propelling a projectile and relates in particular to perforating guns employed in wells to perforate the well casing by shooting projectiles therethrough.

It is an object of the invention to provide a well perforating gun having a plurality of barrels axially movable in a supporting structure, such as a gun body, and means acting in response to forward movement of the gun barrels relatively to the projectiles to ignite or fire the powder charges.

It is a further object of the invention to provide a gun having a movable barrel, with means for holding the projectile so as to restrain or limit movement thereof and means for moving the barrel with relation to the projectile, thereby causing the firing of the powder charge disposed behind the projectile in the barrel. Herein the term "powder charge" is employed to designate those explosive substances which burn with sufficient rapidity to produce a high gas pressure substantially instantaneously against the rear end of the projectile, or which explode with a detonating action.

It is a further object of the invention to provide a gun having a supporting structure or body in which a gun barrel is supported for axial movement in forward direction, there being walls to provide a recess to receive a charge of explosive which, when exploded, will apply force to the gun barrel to move the same forwardly, and thereby accomplish ignition of the powder charge which lies in the barrel behind the projectile, in the manner described in detail herein.

It is a further object of the invention to provide a gun having a body with a chamber, this chamber having an external opening, there being an axially movable barrel in the chamber and a retainer for holding the barrel in the chamber, this retainer having thereon means for controlling the position of the projectile so that when the barrel is moved forwardly, a relative movement between the barrel and the projectile is accomplished, such relative movement being employed to fire the powder charge which lies behind the projectile.

A further object of the invention is to provide a gun of the character herein described, having a channel to receive a priming cord, or equivalent explosive substance, this channel communicating with a space at the rear end of the barrel, so that force from the explosion of the primer cord produces forward movement of the barrel.

2
A further object of the invention is to provide in a gun of the character described herein a sealing means for the barrel which also controls or limits forward movement of the projectile, this sealing means being frangible or removably held so that when the gun is fired, there will be a removal or displacement of the sealing means as the projectile is ejected. A feature of the invention is that this sealing and projectile holding means acts to restrain forward movement of the projectile for a short period of time while gas pressure from the burning of the powder charge builds up behind the projectile, with the result that the projectile is finally expelled from the barrel at high velocity and with great perforating force.

Further objects and advantages of the invention will be brought out in the following part of the specification, wherein I have described specific details of the invention for the purpose of clearly disclosing the same without placing limitation on the scope of the invention defined in the appended claims.

Referring to the drawings which are for illustrative purposes only,

Fig. 1 is a fragmentary partly sectioned view, showing a gun embodying my present invention.

Fig. 2 is an enlarged cross section taken as indicated by the line 2—2 of Fig. 1.

Fig. 3 is a cross sectional view similar to Fig. 2, but showing an alternative form of retaining means.

Fig. 4 is a sectional view similar to Fig. 2, but showing an alternative form of ignition means for the powder charge.

Fig. 5 is a fragmentary sectional view showing an alternative construction for the projectile controlling or holding member.

In Fig. 1 I show the lower portion of a gun body 10, this gun body 10 having a spiral channel or recess 11 in the surface thereof for receiving a primer cord 12. At the lower end of this spiral recess there is a depression or cavity 13 in which a clip 14, held by a screw 15, secures the lower end of the primer cord 12. The use of a primer cord for accomplishing ignition of powder charges in a perforating gun is old and means for igniting the primer cord are well known in the art; accordingly, for simplification of this disclosure, I have not shown the upper end of the gun body 10 which contains the means for igniting or exploding the primer cord 12.

The gun body 10 has therein a plurality of gun barrel receiving chambers 16. These chambers 16 are disclosed as consisting of cylindric bores dia-

metrically reduced at their rear ends so as to form shoulders 17. The rear ends of the chambers 16 are connected through openings 18 with portions of the spiral channel or recess 11, the purpose of this arrangement being to utilize the explosive force of the primer cord 12, through the openings 18 to accomplish gun firing functions as will be hereinafter described.

In each of the chambers 16 there is a cylindric gun barrel 19 having a bore 20 leading inward from the front end 21 of the barrel 19, this bore 20 having at its inner end a powder charge 22, and ahead of the powder charge 22, a projectile 23. To limit forward movement of the barrel 19, a retainer 24 is threaded into the opening 25 of the chamber 16. The forward portion or front end 21 of the barrel 19 is of reduced diameter so as to provide an annular shoulder 25' which confronts and is spaced from the cylindric wall portion 26 of the retainer 24. The retainer 24 has a threaded opening 27 aligned with and slightly larger in diameter than the barrel bore 20. A projectile holding member 28 is threaded into the opening 27, this projectile holding member having a portion 29 which extends into the barrel 19 and confronts or engages the nose of the projectile 23, this holding member 28 controlling the forward position of the projectile 23 in that it limits outward movement of the projectile before and up until the time the perforating gun is fired. The holding member 28 carries thereon a seal 31 for sealing the front end of the barrel 19, this seal 31 consisting of a ring of rubber carried in an annular channel 30 formed in the holding member 28. The holding member 28 is so formed that when the powder charge 22 is exploded, the member 28 will be removed from its position at the front end of the barrel 19. The holding member 28 is shown as being of hollow form and the metal from which it is formed is of such character that the force with which the projectile 23 is propelled outwardly by the firing of the powder charge 22 will result in a shearing of the holding member 28 or a disintegration of the same. A feature of this holding member 28 in addition to the functions hereinbefore ascribed thereto, is that it initially restrains outward movement of the projectile 23 when the powder charge 22 is first ignited. The result of this is that a heavy pressure of gaseous products is built up behind the projectile 23, while, at the same time, outward movement of the projectile 23 is restrained until the pressure of the burning powder charge behind the projectile 23 builds up to a magnitude capable of overcoming the resistance of the plug or holding member 28. When the holding member 28 then yields, the projectile 23 is driven from the barrel at increased velocity and with great penetrating force.

The firing of the perforating gun is accomplished by igniting and exploding the primer cord 12 in any of the manners well known to the art. Through each of the openings 18, the explosive force of the overlying portion of the primer cord 12 is transmitted to the rear end of the barrel 19, driving such barrel forward, while the holding member 28 prevents forward movement of the projectile 23. The forward movement of the barrel 19 causes the rear end wall 32 thereof to move toward the rear end of the projectile 23, compressing the powder charge 22 and causing the same to explode by compression and/or detonation.

In Fig 2 I have shown ports 24a in the re-

70 tainer 24 to permit flow of fluid from the space 33 within the retainer 24 adjacent the front end of the barrel 19. In Fig. 3 I show a form of my invention having a cup-like retainer 24' omitting the ports 24a. To provide for escape of fluid from the space 24b ahead of the barrel 19, ports 34 are drilled through the body 10 in positions to communicate with the space 24b, the plane of communication between the ports 34 and the space 24b being rearwardly of the inner lip of the retainer 24'. Also, in Fig. 3 I show means for preventing inadvertent firing of any of the powder charges 22 in a perforating gun of the type disclosed herein, due to application of a shock or blow tending to shift a gun barrel 19 outwardly in the chamber 16 which holds the same. For this purpose the gun barrel 19 has a depression or socket 35 which receives the inner end of a shear pin 36 which is placed in an opening 37 in the body 10. This shear pin 36 is of such strength as to prevent forward movement of the barrel 19 by any blows or shocks which might be applied to the gun body 10 during the ordinary handling of the same or such as might result from a dropping of the gun body 10. However, the strength of the shear pin 36 is such that it will be sheared by the explosive force applied to the rear end of the barrel 19 when the primer cord 12 is exploded.

75 In the ordinary practice of the invention, a propelling charge or powder 22 is employed which is readily exploded by forward movement of the barrel 19 as previously described herein. However, the invention comprehends the use of auxiliary igniting means in association with the powder charge, so as to assure firing of the powder charge under all circumstances, including the use of an explosive substance which is not fired by compression or where a primer cord is employed which has reduced explosive effect so that the barrel 19 is not driven forwardly with great force. In Fig. 4 I have shown a form of my invention, wherein an ignition means 40 is disposed in the gun barrel 19 behind the projectile 23. This igniting means may consist of a pressure-fired fuse or cap, or it may consist of an air-filled chamber formed by a wall 41 of relatively soft material so that it will collapse when the barrel 19 is driven forwardly, thereby compressing the gas within the chamber of the igniting means 40 so as to raise it to ignition temperature, such gas, at ignition temperature, passing through an opening 42 in the wall 41 into the powder charge 22, igniting such powder charge.

80 In the forms of the invention herebefore shown, the holding member 28 is threaded into the threaded opening 27 of the retainer 24, the purpose of this threaded connection being to prevent inward movement of the holding member 28 by liquid pressure encountered in the well. When the gun is employed in a dry well, this threaded connection between the member 28 and the retainer 24 need not be used, but, as shown in Fig. 5, the retainer 24 may have an unthreaded opening 27' to receive the forward portion of the holding member 28, and the holding member 28 may be provided with an annular shoulder 50 engaging the retainer 24 so as to limit outward movement of the holder 28.

85 I claim as my invention:

1. In a gun, the combination of: a gun barrel having a transverse wall and being adapted to receive therein a projectile and a powder charge behind said projectile, said barrel being supported so that it may have forward movement; a holding

member projecting into the forward end of said barrel and engaging said projectile so as to prevent its forward movement; and means for moving said barrel forwardly so as to compress the powder charge between said transverse wall and the rear end of said projectile and cause ignition of the same.

2. In a gun, the combination of: a gun barrel having a transverse wall and being adapted to receive therein a projectile and a powder charge behind said projectile, said barrel being supported so that it may have forward movement; a holding member projecting into the forward end of said barrel and engaging said projectile so as to prevent its forward movement; and means to apply an explosive force for moving said barrel forwardly so as to compress the powder charge between said transverse wall and the rear end of said projectile and cause ignition of the same.

3. In a gun, the combination of: a gun barrel having a transverse wall and being adapted to receive therein a projectile and a powder charge behind said projectile, said barrel being supported so that it may have forward movement; sealing means on said holding member for preventing entry of fluid into said powder charge; a holding member projecting into the forward end of said barrel and engaging said projectile so as to prevent its forward movement; and means for moving said barrel forwardly so as to compress the powder charge between said transverse wall and the rear end of said projectile and cause ignition of the same.

4. In a gun having means for producing forward movement of its gun barrel, the combination of: a gun body having a chamber with an external opening; a barrel axially movable in said chamber, the forward end of said barrel facing said opening of said chamber, said barrel being adapted to receive a projectile and an explosive charge behind said projectile; and means supported in said chamber having a holding member projecting into said barrel to control forward movement of said projectile so that when said barrel is moved forwardly relatively to said projectile, a compressive ignition effect will be applied to said explosive charge.

5. In a gun, the combination of: a gun body having a chamber with an external opening; a barrel axially movable in said chamber, the forward end of said barrel facing said opening of said chamber, said barrel being adapted to receive a projectile and an explosive charge behind said projectile; means supported in said chamber having a holding member projecting into said barrel to control forward movement of said projectile so that when said barrel is moved forwardly relatively to said projectile, a compressive ignition effect will be applied to said explosive charge; and means for supporting an explosive so that force from the explosion thereof will produce forward movement of said barrel.

6. In a gun having means for producing forward movement of its gun barrel, the combination of: a gun body having a chamber with an external opening; a barrel axially movable in said chamber, the forward end of said barrel facing said opening of said chamber, said barrel being adapted to receive a projectile and a propelling charge behind said projectile; a retainer securable in the opening of said chamber for limiting forward movement of said barrel; and a holding member projecting from said retainer into said barrel to control forward movement of said projectile when said barrel is moved forwardly.

7. In a gun having means for producing forward movement of its gun barrel, the combination of: a gun body having a chamber with an external opening; a barrel axially movable in said chamber, the forward end of said barrel facing said opening of said chamber, said barrel being adapted to receive a projectile and a propelling charge behind said projectile; a retainer securable in the opening of said chamber for limiting forward movement of said barrel; a holding member projecting from said retainer into said barrel to control forward movement of said projectile when said barrel is moved forwardly; and means on said holding member for sealing the outer end of said barrel.

for sealing the outer end of said barrel.

8. In a gun having means for producing forward movement of its gun barrel, the combination of: a gun body having a chamber with an external opening and having a recess for an explosive communicating with the rear end of said chamber; a barrel axially movable in said chamber, the forward end of said barrel facing said opening of said chamber, said barrel being adapted to receive a projectile and a propelling charge behind said projectile; a retainer securable in the opening of said chamber for limiting forward movement of said barrel; a holding member projecting from said retainer into said barrel to control forward movement of said projectile when said barrel is moved forwardly; and means on said holding member for sealing the outer end of said barrel.
